CLAIM

The ornamental design for a coil for expansion valve as shown and described.

DESCRIPTION

FIG. 1 is a front, left side, and top perspective view of a coil for expansion valve comprising a new, original and ornamental design;

FIG. 2 is a top view thereof;

FIG. 3 is a bottom view thereof;

FIG. 4 is a front view thereof;

FIG. 5 is a back view thereof;

FIG. 6 is a left side view thereof; and,

FIG. 7 is a right side view thereof.

The broken lines illustrate portions of the coil for expansion valve and form no part of the claimed design. The coil for expansion valve is shown with symbolic breaks in its length. The appearance of any portion of the coil for expansion valve between the break lines forms no part of the claimed design.
